UNITED STATES PATENT OFFICE.

WILLIAM A. COLVER, OF MARSHFIELD, OREGON.

STEAM-ESCAPE VALVE FOR RANGE-BOILERS, &c.

1,401,048.

Specification of Letters Patent. Patented Dec. 20, 1921.

Application filed February 8, 1918. Serial No. 216,054.

To all whom it may concern:

Be it known that I, WILLIAM A. COLVER, a citizen of the United States, residing at Marshfield, in the county of Coos and State 5 of Oregon, have invented certain new and useful Improvements in Steam - Escape Valves for Range-Boilers, &c.; and I do hereby declare the following to be a full, clear, and exact description of the invention, 10 such as will enable others skilled in the art to which it appertains to make and use the same.

The invention relates to steam escape valves for range boilers, etc.

15 The object of the present invention is to provide a simple, practical and efficient steam escape designed for use in connection with range boilers and the like and capable of permitting the escape of steam accumulating in the top of the boiler and at the same time of preventing water from passing out through the steam escape.

20 With these and other objects in view, the invention consists in the construction and 25 novel combination of parts hereinafter fully changes in the form, proportion, size and drawing and pointed out in the claim hereto appended; it being understood that various 30 changes in the form, proportion, size and minor details of construction, within the scope of the claim, may be resorted to without departing from the spirit or sacrificing any of the advantages of the invention.

In the drawing:

35 Figure 1 is a side elevation of a steam escape valve constructed in accordance with this invention and shown applied to a range boiler.

40 Fig. 2 is an enlarged vertical sectional view of the steam escape valve.

Fig. 3 is a horizontal sectional view of the same on the line 3—3 of Fig. 2.

45 Like numerals of reference designate corresponding parts in all the figures of the drawing.

In the accompanying drawing, in which is 50 illustrated the preferred embodiment of the invention, the steam escape valve comprises in its construction a valve casing composed 55 of an upper valve chamber 1 and a lower float chamber 2 which is connected at the upper end with the lower end of the valve chamber. The valve chamber, which may be conveniently formed by a T-coupling, is 60 provided at the upper end with a valve seat 3, preferably carried by a steam escape

65 pipe or steam outlet 4 which is threaded into the said T-coupling. The T-coupling is preferably arranged with its opposite arms disposed vertically, one of the opposite arms being connected to the steam outlet or escape pipe 4, and the other to the upper end of the float chamber 2. The third arm of the T-coupling is disposed horizontally and is connected to one end of a steam inlet pipe by 70 threading the latter into the same as shown at 5. The steam inlet or steam pipe 6, which is connected with the upper end of a range boiler 7, has a coupling 8 and a union 9 and it permits steam which generates on the top 75 of the range boiler to pass therefrom into the valve chamber 1. The steam pipe 6 may be of any other desired construction and the valve chamber is located above the plane of the top of the boiler and it receives a valve 80 member or valve proper 10 operating in the valve chamber and carried by the upper end of the vertical stem or rod 11 which is secured at its lower end to a float 12. The float 85 12 is located within the float chamber 2 which is composed of a cylindrical body and upper and lower caps or sections 13 and 14 threaded on the ends of the body portion but it may be secured to the same in any other desired manner as will be readily understood. The valve stem or rod 11 passes through a central opening 15 in a horizontal 90 guide or spacer 16 consisting of a disk secured within the upper end of the vertical body portion of the float chamber and provided with a plurality of openings 17 for the passage of water and steam. The upper cap 13 is provided with a neck 18 which is threaded into the coupling which constitutes the valve chamber, and the lower section 14 95 is also provided with a neck 19 which receives the threaded upper end 20 of a pipe 21 piercing the side of the boiler and extending into the same and adapted to permit the water to recede from the float chamber. 22 100 and 23 designate the cold and hot water pipes extending to and leading from the boiler. In the operation of the steam escape valve the steam which is generated in the top of the boiler passes through the steam 105 pipe into the steam chamber and in accumulating therein causes the water to recede in the float chamber sufficiently to permit the float to descend and open the valve and permit the steam to escape through the steam 110 outlet or steam pipe 4. The rising of the water in the float chamber with the escape

of the steam will cause the valve to close and prevent any escape of the water.

What is claimed is:

In combination with a boiler, a valve, a chamber therefor, a conduit for steam leading from a point adjacent to the top of the boiler to said chamber, a steam escape means leading from the chamber, a cylinder below said chamber into which water from the chamber drains in communication with the boiler, said valve normally closing the steam escape pipe, said valve having a float in the said cylinder, said chamber and cylinder being in communicating relation substantially unobstructed to effective expansion of steam

therein, said construction permitting the accumulation of steam in the chamber to displace water in the cylinder so that the valve will thus automatically recede to permit escape of excess steam through the escape pipe and subsequently move against its seat through rising of the water level in the boiler and cylinder. 20

In testimony whereof I affix my signature in presence of two witnesses.

WILLIAM A. COLLVER.
